Primary Examiner — Clare E Heflin

(74) Attorney, Agent, or Firm — Timothy W. Menasco,
 Esq.; Harter Secrest & Emery LLP(57) **CLAIM**

The ornamental design of a lighting fixture, as shown and described.

DESCRIPTION

FIG. 1 is a bottom perspective view of a lighting fixture in accordance with the present invention;

FIG. 2 is a front view thereof, a rear view being the mirror image thereof;

FIG. 3 is a top view thereof; and,

FIG. 4 is a bottom view thereof.

The broken lines of the Figures are for illustrative purposes only and form no part of the claimed design.
